UNITED STATES PATENT OFFICE.

MARVIN H. JESTER, OF DENVER, COLORADO, ASSIGNEE TO THE M. H. JESTER INVESTMENT COMPANY, A CORPORATION OF COLORADO.

CLIP FOR SECURING PLASTER-BOARDS TO METAL STUDDING IN PARTITION CONSTRUCTION.

1,125,335.

Specification of Letters Patent. Patented Jan. 19, 1915.

Application filed March 29, 1913. Serial No. 757,584.

To all whom it may concern:

Be it known that I, MARVIN H. JESTER, a citizen of the United States of America, residing in the city and county of Denver and State of Colorado, have invented a new and useful Clip for Securing Plaster-Boards to Metal Studding in Partition Construction, of which the following is a specification.

My invention relates to an improved metallic clip that is adapted to be used with metallic studding and plaster boards as a skeleton wall or support for plastering materials in constructing plastered partition walls in buildings.

15 The objects of my invention are: First. To provide a cheap and simple clip for securing plaster boards to metal studding and particularly to channel bar studs. Second. To provide a clip that can be folded by 20 the workman around the stud, thus enabling any number of clips to be secured in position on the studding that is necessary to support plaster boards of different thicknesses. And third. To provide a clip 25 that when mounted on a stud is closed together and the opposite sides support each other and prevent the wings being bent backward beyond their normal right-angled position. I attain these objects by the mechanism illustrated in the accompanying drawings, in which:

Figure 1 is a perspective view of one of my new clips mounted on a channel bar stud and adapted to be used to support plaster boards of about a quarter of an inch in thickness. Fig. 2 is a top view of Fig. 1. Fig. 3 is a perspective view of my improved clip arranged and adapted to be used to support plaster boards of about three-quarters 35 of an inch in thickness. Fig. 4 is a top view of Fig. 3. Fig. 5 is a plan view of a flat blank clip as it is punched out of ribbon iron or steel. Fig. 6 is a top view of the flat blank clip as it is bent by the operator 40 around a channel bar. Fig. 7 is a front elevation of a portion of a plaster board partition showing the application of my new clip to metal studs to support the plaster boards in skeleton partition form, ready to 45 receive the plastering materials. And Fig. 8 is a view of the clip as it is first bent by dies after it is stamped out into a flat blank, and represents the form in which it is 50 shipped in large numbers to contractors.

Similar letters of reference refer to similar parts throughout the several views.

Referring to the drawings, the numeral 1 designates a metal stud, preferably a channel bar stud, as I preferably use the channel bar form of stud in preference to other forms of metal stud, such as flat metal bars, T bars, Z bars, or V bars; 2 designates the wing portions of my new clip. From one side of these wings a yoke portion 3 extends, which is made long enough and of a width 55 to fit over the size of channel bar I preferably use, which is preferably three-quarters inch channel bar, as this size channel bar makes what I term a 2 inch plastered partition when plaster boards of either one-quarter or three-quarters of an inch in thickness are used. At the junction of the sides of the yoke portion with the wings of the clip, tongue portions 4 and 5 are cut free from the opposite sides of the yoke portion 60 which I term the locking lugs. These tongue shaped locking lugs are bent to stand parallel with the wings and to extend from opposite sides of the extreme lower end portion of the yoke portion of the clips 65 across the open space between these ends and close it when the clip is folded around the channel bar, each tongue shaped locking lug being long enough to extend preferably half way across the open space, and they are 70 positioned opposite to each other so that their ends preferably abut together or nearly so when the clip is manually folded around a channel bar by an operator, as will be presently described. I prefer that these 75 locking lugs shall come together so that their ends either meet or come close to it when the clip is folded around a channel bar with its wings at right angles to the yoke portion of the clip in position to receive the plaster board, and thus act as a stop to bending the wings back beyond the 80 right angular plane to the yoke portion they belong in, to receive and act as an abutment support for the plaster boards, as shown in Fig. 2, in which these locking lugs are shown 85 abutting together at the same time the wings are at right angles to the sides of the yoke portion and are in a horizontal plane with the quarter inch plaster board keyed by the 90 nail flat against the wings.

The closed end of the yoke portion of the clip is provided with an aperture 6, in Fig.

- 1, which is placed therein to get rid of some of the metal along the side or corner edges of the closed top of the yoke portion of the clip so that the same blank form shown in Fig. 6 will always bend easily at these corner edges when the semi-blank form of a clip is laid across a channel bar by a workman and bent finally into its final and true form around the channel bar, as shown in Figs. 1, 2, and 6.
- 10 In Fig. 3, I illustrate a clip provided with a slot 7 along each side edge of the closed top portion of the yoke of the clip. These slots not only facilitate the final accurate bending movement of the clips across a channel bar at these corners, but these corner slots are necessarily placed at the corners of the top side edges when plaster boards of three-quarters of an inch in thickness are used instead of the single aperture in the top, as shown in Fig. 1, as it is impossible to insert a keying nail 8 through the channel bar when plaster boards of this thickness are used, as the plaster boards are 20 a trifle thicker than the height of the yoke portion of the clip and they cover the channel bar, and these side edge slot apertures enable me to raise the central portion of the closed top end of the yoke and into a loop 25 of metal that is arranged and adapted to form the housing band 9 for a keying nail 8 which in Figs. 1 and 2 is inserted through apertures punched in the channel bar below the clips, as shown in my issued Patent 30 Number 1,001,146, issued to me August 22, 1911, in which construction and arrangement of clips and channel bars, plaster boards of a quarter inch in thickness are used. I preferably, however, in order to facilitate the 35 bending of the clip at the side edges of the narrow central portion of it that is closed over one edge and the sides of the stud, provide this central portion with a concavo-convex crease or groove 10, adapted to be 40 placed against the edge of the channel bar when the clip is placed against it and bent around its edge and against its sides, as shown in Figs. 8 and 6. In Fig. 6, however, this concavo-convex groove is not present as 45 it flattens out and disappears when the clip, as illustrated in Fig. 8, is laid with the point 50 of the concavo-convex groove or crease against the edge of the channel bar and the clip is bent or folded toward the sides of the 55 channel bar as shown in Fig. 6, in which it will be seen that this concavo-convex crease or groove has disappeared. It operates to 60 make the clip bend positively at the side edges of the center aperture 6 or in line with the side edge apertures 7, but as it disappears when the clip is fully bent or folded around the channel bar, it is not illustrated in Figs. 1, 3, 4, and 6.
- The operation of my new manually folded 65 clip is as follows: The blank clip is first stamped, punched or cut out of ribbon iron or steel, into a flat blank, as shown in Fig. 5, and the locking lugs 4 and 5 are cut free from the metal and the aperture 6 or apertures 7 are formed in the blank. The flat 70 blank is then placed in dies and is bent into the shape shown in Fig. 8, and the clips in that shape are shipped to contractors to be used in erecting plaster board partitions. The workman erecting a plaster board partition with my new clips erects the channel bar studs first, at such distances apart vertically as will receive between them the plaster boards, which are made in sizes of two feet square and two feet by three feet square, 75 and in other sizes. The workman then takes the clips as shown in Fig. 6, one at a time, and lays them centrally on the channel bar with their central aperture or apertures directly over the adjacent edge of the channel bar, and bends their opposite sides back against the sides of the channel bar, which causes its locking lugs to extend under the opposite edge of the channel bar until they strike together, which will bend the wings 80 back until they stand in a plane at right angles to the sides of the yoke portion of the clip, in which position they are ready to receive the plaster boards which are laid 85 against them, and the keying nails are inserted either through the channel bar or through the top of the clips, as the case may be. The slot or slots of the top closed end of the clips are positioned to permit the semi-blank clip to bend at the side corners to 90 form a space between the sides of the yoke portion of the clips after they are folded, of just enough less width than the channel bar to cause the clip to stick to the channel bar at its closed corners, which will hold the clip 95 where it is placed and prevent it from sliding down on the channel bar.
- 100 My new and improved clip is simple in construction and can be easily and quickly applied by workmen to channel bars to support plaster boards in skeleton partitions for receiving plastering materials.
- 105 Having described my invention, what I claim as new and desire to secure by Letters Patent, is:
- 110 1. A metallic clip for metallic studding and plaster board partitions, comprising a flat metal blank clip provided with an apertured central portion to enable it to be manually bent easily when applied to a stud, and provided with a free tongue portion on each side of said apertured bending portion, and having portions beyond said free tongue portions arranged to form plaster board supporting wings, said clip having means at 115 the base of said tongues for facilitating manual bending at said base when being applied to a stud when erecting plaster board partitions.
- 120 2. In a metallic clip for metal studding 125

- and plaster board partitions, the combination of a clip having its center apertured and creased to define its bending points when bent over a stud by an operator, a 5 tongue portion formed on each side of said apertured and centrally creased portion, said clip having end portions beyond said tongue portions arranged to form plaster board supporting wings, said tongues being positioned to be folded over the opposite edge of 10 the stud from the edge of the center of the clip is folded on, said clip being bent from its flat form into a substantially inverted channel-shape, and with its tongue portions 15 extending in alignment with its wing portions and standing parallel to each other and at right angles to its center apertured and creased portion.
3. In a metallic clip for metallic studding and plaster board partitions, the combination of a sheet metal clip arranged to be laid against and bent or folded around a channel stud, said clip being provided with a concavo-convex crease or groove, said 20 crease or groove being positioned at such an intermediate portion of its ends as will leave a plaster board supporting wing on each side of it, said clip being provided with an aperture adjacent to said concaved portions, 25 said concaved portion being arranged to permit the central portion of said clip to bend on both sides of it and at the edges of its aperture and in a direction away from said concavo-convex crease or groove, so 30 that said concavo-convex crease or groove is arranged to offer resistance to the bending of said clip at said center portion and to straighten out after the clip is bent on the edge of a stud.
4. In a metallic clip for metallic studding and plaster board partitions, comprising a U-shaped clip having a central portion containing at its center a concaved crease and apertures at the side of said crease, said center portion being arranged to be laid against 45 one edge of a stud and to be bent manually at its apertured corners, tongue portions freed from said center portion and arranged to stand at right angles, and wing portions 50 arranged at substantially right angles to said center portion and extending in an opposite direction from said tongue portions, said U-shaped clip being adapted in this form to be bent by an operator around a 55 stud in position to support plaster boards, and means including a nail extending through the apertured portions of the center of said clip for securing the plaster boards to said wings.
5. In a metallic clip for metallic studding, the combination of the channel stud provided with nail receiving apertures, and plaster boards, of a U-shaped clip provided 60 with an apertured center portion creased to bend more readily at each side of its aper- 65 tured center than at any point immediately adjacent to said apertured center when said central portion is laid against one edge of a stud and the end portions of said stud are bent to the sides of said stud, said clip being 70 provided with tongue portions freed from said clips at a sufficient distance from said apertured center portion as to allow said tongue portions to be folded around the opposite edge of said stud from the edge 75 against which it is bent, said clip being arranged so that the cutting loose of said tongue portions from it will allow it to be bent to form oppositely extending wing portions adapted to support plaster boards, 80 and means including nails extending through said studs, for securing said plaster boards to the wings of said clip.
6. A securing device for plaster-boards, comprising a stud, a clip-plate having a 85 body-portion adapted to engage the forward part of said stud, outwardly and oppositely extending wing-portion, and inwardly extending members lying in the same plane with said wing-ports, and 90 adapted to engage the rear of said stud, and means at the forward part of said stud for securing the plaster-boards against said wings.
7. A securing device for plaster-boards, comprising a stud, a U-shaped clip adapted to surround the forward part of said stud, said clip having at its free ends outwardly and oppositely extending wing-ports and inwardly extending members lying in the same plane with said wing-ports adapted to engage the rear of said stud, and means at the forward part of said stud for securing the plaster-boards against said wings.
8. A securing device for plaster-boards, comprising a stud, a U-shaped clip adapted to surround the forward part of said stud, said clip having at its free ends integral outwardly and oppositely extending wing-ports and integral inwardly extending tongues lying in the same plane with said wing-ports adapted to engage the rear of said stud, and means at the forward part of said stud for securing the plaster-boards against said wings.
9. A securing device for plaster-boards, comprising a stud, a U-shaped clip adapted to surround the forward part of said stud, said clip having at its free ends outwardly and oppositely extending wing-ports and inwardly extending tongues adapted to engage the rear of said stud, and having its closed end slotted, and a key passing 110 through the slotted portion of said clip 115 and lying along the front of said stud for securing the plaster-boards against said wings.
10. A securing device for plaster-boards, comprising a stud, a U-shaped clip adapted 120 125 130

to surround the forward part of said stud, said clip having at its free ends outwardly and oppositely extending wing-portions and inwardly extending tongues adapted to engage the rear of said stud, said clip having its closed end slitted along two lines, the portion of the clip between said slits being bent away from the clip to form a keyway, and a key in said keyway for securing the plaster-boards against said wings.

11. A securing device for plaster-boards, comprising a stud, a U-shaped metal clip adapted to surround the forward part of said stud, said clip having at its free ends outwardly and oppositely extending wing-portions, tongues on said clip adapted to engage the rear of said stud, said clip having each side of its closed end slitted along two vertical lines, the metal between said slits being bent away from the clip to form a keyway, and a key passing horizontally

through said keyway and adapted to engage the plaster-boards on each side of the clip to secure said plaster-boards against said wings.

12. A clip for plaster-boards, having a body-portion adapted to be bent around the stud; said body-portion having angularly disposed ends forming when said body-portion is bent around the stud wings approximately flush with the rear edge of said stud against which the plaster-boards are secured, and having tongues in alignment with said wings engaging the rear of the stud when said body-portion is bent around the stud.

In testimony whereof I affix my signature in presence of two witnesses.

MARVIN H. JESTER.
